CABINET DOOR CATCH

Earl M. Borchers, Rockford, Ill., assignor to American Cabinet Hardware Corporation,
Rockford, Illinois, Rockford, Ill., a corporation of Illinois

Application March 19, 1953, Serial No. 24,124

Term of patent 14 years

(Cl. D10—8)

To all whom it may concern:

Be it known that I, Earl M. Borchers, a citizen of the United States, residing at Rockford, in the county of Winnebago and State of Illinois, have invented a new, original, and ornamental Design for a Cabinet Door Catch, of which the following is a specification, reference being had to the accompanying drawing forming a part thereof, wherein:

Fig. 1 is a top plan view of a cabinet door catch embodying my new design.

Fig. 2 is a side elevation of the design illustrated in Fig. 1 and showing in broken lines mounting studs which are hidden from view when the catch is installed.

Fig. 3 is an end elevation of the device shown in the preceding figures.

I claim:

The ornamental design for a cabinet door catch, as shown and described.

EARL M. BORCHERS.
